PICTURE ILLUMINATING MEANS

John F. Shaffer, Mentor, Ohio

Application August 21, 1939, Serial No. 291,262

3 Claims. (Cl. 88—24)

This invention relates to an illuminating means for pictures, the general object of the invention being to provide means associated with an electric bulb for casting a bright light upon a picture or other object and means for focusing the light upon the object and also to provide means for regulating the size of the opening through which the light passes.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a front view of the invention.

Figure 2 is a section on the line 2—2 of Figure 1.

Figure 3 is a section on the line 3—3 of Figure 1.

Figure 4 is a fragmentary rear view showing the means for adjustably connecting the reflector to the body member.

Figure 5 is a view of the adjustable two parts mask.

Figure 6 is an edge view of the mask.

In these views the numeral 1 indicates an electric lamp bulb socket for receiving a lamp bulb 2 in the usual manner and in carrying out my invention I provide a substantially spherical-shaped body member 3 which has a hole in its lower end through which the socket passes and said lower part being connected with a portion of the socket by the screws 4, the parts being so arranged that the socket can be screwed into an outlet box or socket member to provide current to the bulb 2. The top of the body 3 is cut away to provide the large opening 5 and it is also provided with the ventilating louvers 6. At the rear the member 3 is provided with a vertical slot 7 through which passes a bolt 8 fastened to the center of a reflector 9 located in the body 3 and a thumb nut 10 engages the projected part of the bolt for adjustably holding the reflector with the bolt 8 in the slot 7. An opening 11 of substantially oval shape and vertically arranged is formed in that side of the member 3 opposite the side to which the reflector 9 is connected and arcuately arranged guideways 12 are located at opposite sides of said opening 11 for a housing 13 so that the housing can be adjusted vertically to place the lens carrying barrel 14 in horizontal or upwardly

or downwardly sloping positions. The lens barrel is slidably arranged in the front and reduced part of the housing so that it can be moved inwardly or outwardly to focus the light in the usual manner and in rear of the barrel are arranged the guideways 16, one on each side of the opening leading to the barrel and these guideways are to receive the mask 17 which is composed of the short and wide part 18 and the long and narrow part 19, this part 19 having the lateral narrow extension 20 at its lower end, the lower edge of which is rounded as shown in Figure 5, while the member 18 has the angle cut out 21 in its lower end. Thus by adjusting the members 18 and 19 relatively to each other the opening 22 formed by the angle opening 21 and the lower part of the portion 19 and the part 20 can be adjusted as to size as shown in Figure 6 these parts 18 and 19 are bowed so as to frictionally fit within the guideways 16 which will cause the parts to remain in adjusted position after once being adjusted. Thus it will be seen that the opening 22 through which the light passes from the source to the lens barrel can be adjusted and, of course, by adjusting the lens barrel 10 the light rays can be focused on an object placed in front of the lens barrel and by adjusting the mask section the light can be focused on any desired part of the object, such as a picture of a person in a group photograph. Also the housing 13 with the lens barrel can be raised and lowered on the guide 12 and if desired a shade can be used with the device as shown at S in dotted lines in Figure 2.

By moving the housing 13 in the guides 12 the rays of light can be adjusted on an object at the desired elevation and if necessary or desired the reflector 9 can also be adjusted in accordance with the adjustment of the lens barrel.

Having described the invention, what is claimed as new is:

1. An illuminating device comprising a substantially spherical body having an opening in a side part thereof of elongated form and vertically arranged, a lamp in the body, arcuate and vertically arranged guideways carried by the body, one at each side of the opening, a housing having an arcuate-shaped inner end guided by said guideways for movement in an arc of a circle having the lamp as its axis, said housing receiving the rays of light from the lamp, through the opening, in all positions of the housing relative to the opening and a lens barrel carried by the housing.

2. An illuminating device comprising a sub-

stantially spherical body having an opening in a side part thereof of elongated form and vertically arranged, a lamp in the body, arcuate and vertically arranged guideways carried by the body, one at each side of the opening, a housing having an arcuate-shaped inner end guided by said guideways to be adjusted opposite different parts of the opening to receive the rays of light from the lamp, a lens barrel carried by the housing, a reflector in the spherical casing on that wall which is opposite the wall having the opening therein for reflecting the rays of light from the lamp through the opening and means for adjusting the reflector vertically.

15 3. An illuminating device of the class described comprising a substantially spherical body having an opening in its top, a vertically arranged elongated

5 opening in a side part thereof and a vertically arranged slot in a side part which is diametrically opposite the side part having the elongated opening therein, a housing having an arcuate-shaped inner end for fitting over the elongated opening, arcuate and vertically arranged guideways carried by the spherical body, one on each side of the elongated opening for said inner end of the housing, a reflector, a bolt carried thereby and passing through the slot and having 10 a nut on its outer end for holding the reflector in adjusted position, a lens barrel carried by the housing through which the rays of light pass from the lamp after it has passed through the 15 elongated opening into the housing.

JOHN F. SHAFFER.
